CARBURETER.

1,205,693.

Specification of Letters Patent. Patented Nov. 21, 1916.

Application filed February 13, 1915. Serial No. 8,046.

To all whom it may concern:

Be it known that we, SIDNEY WOOLF and FRED E. HALE, citizens of the United States, residing, respectively, at Lynch, in the county of Boyd, and at South Omaha, in the county of Douglas, both in the State of Nebraska, have invented certain new and useful Improvements in Carbureters, of which the following is a specification.

10 Our invention relates to the general class of internal combustion engines, and more particularly to charge-forming devices or carbureters for use in connection with engines of this class.

15 It is the object of our invention to provide in a carbureter means by which two liquid fuels such as gasolene and kerosene may be used interchangeably for the production of the combustible mixture, means

20 for distributing the fuel to a plurality of points from which it may be taken up and drawn into the engine together with a suitable quantity of air, means for thoroughly disintegrating or atomizing and mixing the

25 fuel with the air during the passage thereof toward the engine so that the fuel will be thoroughly vaporized before entering the engine, means for pre-heating the air supplied to the distributing and mixing devices,

30 means for supplying suitable quantities of water-vapor along with the pre-heated air, means for pre-heating the heavier fuel and for maintaining a supply of the pre-heated fuel in immediate proximity to the distributing and mixing devices, means for throttling or controlling the flow of the combustible mixture from the carbureter to the engine, means actuated synchronously with the throttle for varying the fuel supply according to the quantity of combustible mixture produced, means also actuated synchronously with the throttle for retarding or varying the resistance to the flow of material through the mixing devices so as

40 to control the rate of flow through the same, means for automatically supplying a priming-charge of fuel for starting the engine, means for temporarily restricting the supply of air to the distributing and mixing devices when it is desired to form a richer mixture as in starting the engine, and various other specific structures and combinations of parts which will be hereinafter described in detail.

A structure embodying our invention is 55 illustrated in the accompanying drawings, in which—

Figure 1 is a longitudinal vertical sectional view of the carbureter, together with a side view, partially sectional, of the 60 heater for supplying heated air, fuel and water-vapor to the carbureter proper, Fig. 2 is a transverse vertical sectional view of the carbureter, Fig. 3 is a horizontal sectional view on the plane of the line $x-x$ of 65 Fig. 1, showing the throttle from below, Fig. 4 is a detail sectional view on the plane of the line $y-y$ of Fig. 1, showing the distributor and fuel-controller from above, Fig. 5 is a detail bottom view of the distributor as seen when the casing is separated 70 on the plane of the line $z-z$ of Fig. 1, Fig. 6 is a side view of the carbureter, showing the controlling connections thereof, and Fig. 7 is a detail vertical section on the plane of 75 the line $o-o$ of Fig. 4, showing the feed-port for the priming-cup.

In the illustrated structure we provide an integral main casing comprising an annular central portion 1 and cylindrical cups 80 2 and 3 disposed on opposite sides thereof. Covers 4 and 5 are provided for the cups, which form fuel-chambers 6 and 7 for containing, respectively, the lighter or more volatile liquid fuel and the heavier fuel. 85 In the bottoms of the cups are removable valve-seats 8 and 9 which extend down into screen-chambers 10 and 11 formed within the caps 12 and 13 secured on the bottoms of the cups. The lighter fuel is supplied 90 through a pipe 14 to the chamber 10, and the heavier fuel is supplied through a pipe 15 to the chamber 11. Cylindrical screens 16 are disposed in the chambers 10 and 11 surrounding the valve-seats 8 and 9, so as 95 to strain the fuel and exclude from the valves all except very minute particles of solid matter. It will be noted that the screens are of large area so as not to become clogged and require cleaning except after long- 100 continued use. The openings through the valve-seats 8 and 9 are controlled by needle-valves 17 and 18, the valves being actuated by floats 19 and 20 so as to maintain a constant level of the liquid fuels in the chambers 6 and 7.

In the casing between the cups 2 and 3 and the central portion 1 are transverse

openings in which are placed rotatable valves 21 and 22 controlling passages from the fuel-chambers to the distributor. On the stems of said valves are secured cranks 5 23 and 24 which are connected to each other by a rod 25. A rod 26 is also connected therewith, as shown in Fig. 6, so that by longitudinal movements of the same the valves may be operated simultaneously to 10 open one and close the other of the passages from the fuel-chambers to the distributor.

The distributor comprises a vertically-perforate base-portion 27 disposed within the casing-portion 1 and having horizontal 15 passages communicating with the valve-controlled passages to the fuel-chambers, and a tubular portion 28 which extends up from the base-portion into a chamber 29 formed within a casing-member 30 which is secured 20 on top of the casing-portion 1. As shown in Figs. 1 and 5, the part 27 has a central hub which forms a bearing for the shaft or rod 35. Connected with this hub by radial 25 arms is an annular portion which is of the same diameter as the tubular part 28, and extending outward from said annular portion are other radial arms of which the ends rest on a ledge or inwardly extending flange on the casing. Air passes between both the 30 inner and outer radial arms. In two of the outer radial arms are horizontal passages, which connect with the respective passages from the valves 21 and 22, and which at their inner ends extend up to the bottom of 35 the tubular part 28. At the bottom of the tubular portion 28 is an annular passage 31 communicating with both the passages extending through the base-portion 27 to the fuel-chambers. In each of the two opposite 40 quadrants of the tubular member 28 are a plurality of vertical passages 32 each connecting at the lower end with the annular passage 31, and at the upper end through a very small opening with a transverse passage or port 33. The passages 33 extend 45 radially through the upper part of the member 28 at a level slightly above the fuel-level in the chambers 6 and 7, and the ends of said passages may be closed or opened 50 by means of the fuel-controller 34. The fuel-controller is a revolute body having a central hub connecting two oppositely-disposed sector-shaped pieces of which the outer parts rest on the upper end of the 55 member 28, and of which each has an inner and an outer flange extending downwardly over the sides of the member past the ends of the passages 33. The hub-portion of the fuel-controller is secured to a vertical rod 60 35 which is journaled at the lower end in the central portion of the base 27. Beneath the latter a gear-segment 36 is secured to the rod, and said segment meshes with a similar segment 37 secured on a small shaft or rod 65 38 which is revolvably mounted in a vertical

position at one side of the casing, as clearly shown in Fig. 2. On the upper end of the rod 38 is a crank 39 which may be actuated as hereinafter set forth, to rotate the rod 38, thereby causing through the geared connection a similar rotative movement of the rod 35 and the fuel-controller. When the controller is in one extreme position the flanges thereof cover all of the passages 33, and as it is rotated the passages are successively 75 uncovered until at the other extreme of movement all of the fuel-ports are open.

At one side of the distributor there is an additional vertical passage 40 communicating at the bottom with the annular passage 80 31, and at its upper end having a lateral outlet through a small port 41 at a level slightly below the normal fuel-level in the chambers 6 and 7. When the controller is in closed position the port 41 is open and allows a 85 small quantity of the liquid fuel to flow out into the annular priming-cup 42 which encircles the body 28, as shown, and of which the upper edge is slightly above the fuel-level. At one side the outer flange of the 90 controller is extended down into the priming-cup far enough to cover and to close the end of the port 41 when the controller is moved from the closed toward the open position thereof, thus preventing the filling 95 of the priming-cup when the controller is in open or intermediate position, and permitting the filling of the priming-cup when the controller is in closed position.

Above the distributor-chamber 29 the casing-member 30 has a contracted or necked portion, above which it extends out again to the normal diameter, and at the upper end has secured to it the cylindrical casing-member 43 which incloses the mixing-chamber 44. The upper end of the casing-member 43 is internally threaded, and into the same is screwed the lower portion of the flanged coupling 45. Set-screws 46 are provided for holding the coupling in any position to which it may be turned, so that when the flanges at the upper end thereof are connected with the intake-manifold pipe of an engine the body of the carburetor may extend longitudinally at any angle thereto. In the lower part of the coupling is the throttle-seat 47 which has sector-shaped openings through it, and beneath the seat is the throttle 48 which is secured on the upper end of the rod 35 so as to be rotated simultaneously with the fuel-controller, the parts being so arranged that the closed positions of the throttle and of the controller are coincident.

In the mixing-chamber 44 beneath the 125 throttle are disposed a plurality of horizontal screens 49, made of wire fabric, the same being held in spaced relation by tubular sleeves 50 fitting within the casing-member 43, as shown. Below the lower screen and 130

resting on an internal flange at the bottom of the member 43 is an annular deflecting-plate 51 of which the inner portion adjacent to the central opening is curved upwardly as shown. In the space below the deflecting-plate 51 is disposed a deflecting-valve comprising an inverted conoid body 52 which fits slidably around the vertical rod 35, and of which the upper peripheral portion rests against the necked portion of the casing-member 30 when the valve is in its lower-most position. The deflecting-valve may be moved up to the position indicated by dotted lines in Fig. 1, by means of an arm 53 which enters a notch in one side of the lower part of the valve-body. Said arm 53 is secured to a small shaft 54 which extends transversely through a lug at one side of the casing-member, and to the outer end of said shaft is secured an arm or crank 55 which is connected by a rod 56 with a lever 57 fulcrumed on the casing as shown in Fig. 6. To said lever there is also connected a rod 58 extending to the crank 39 on the shaft 38 which actuates the fuel-controller and throttle, and the parts are so connected that when the throttle and fuel-controller are in closed position the deflecting-valve will be in the closed position shown in Fig. 1, while when the throttle and controller are in full open position the deflecting-valve will be in the raised position indicated by dotted lines in Fig. 1. The lever 57 is actuated by a rod C or other suitable means extending to the point from which it is desired to control the action of the carbureter.

All the air supplied to the carbureter is drawn through a device for pre-heating the same to a desirable temperature. In the structure shown the heating device comprises a cylindrical casing 59 disposed around an inclined portion of the engine exhaust-pipe E, the openings for the pipe through the ends of the casing being serated, as shown, to provide inlets for cold air. From the upper part of the heater-casing a pipe 60 extends to the carbureter, said pipe connecting with a jacket 61 surrounding the fuel-chamber 7. The fuel-pipe 15 through which oil is supplied to the chamber 7 is also passed through the heater and is carried down through the air-pipe 60 to connect with the cap inclosing the screen-chamber 11, said cap also being inclosed by the jacket 61, so that the pre-heated fuel has no opportunity to become cooled before entering the distributing and mixing devices. A check-valve 62 is provided, as shown, for preventing flow of the heated fuel back to the supply-tank after it has once entered the portion of the pipe within the heater.

On the bottom of the casing-portion 1 is secured a casing-member 63 inclosing the air-chamber 64, the latter communicating 65 with the distributer-chamber 29 through the

vertical perforations in the base-portion of the distributer. The air-chamber 64 connects with the space inside the jacket 61, the opening between the same being controlled by a slide-plate or damper 65, by which the supply of air may be restricted in order to form a richer mixture when starting the engine.

Around the exhaust-pipe E within the heater-casing there is placed a pad 66 of suitable porous or fibrous non-combustible material, such as asbestos, and said pad may be kept moistened with water supplied through a perforate pipe 67 extending into the casing as shown. The water so supplied, being vaporized by heat from the exhaust-pipe, rises to the upper part of the casing and is drawn through the air-pipe 60 to the carbureter. Water-vapor is thus furnished in appropriate quantities and is mingled with the combustible mixture supplied to the engine. The supply of water-vapor is essential for successful operation of an engine when kerosene or the like is used as a fuel, and may be advantageously employed with lighter fuels such as gasoline.

In general the operation of the described mechanism will be obvious. It may be noted, however, that the control of the carbureter is positive throughout, there being no springs or spring-controlled valves employed in it, and all controls being so correlated that a minimum of adjustment is necessary to secure the greatest efficiency under all conditions of operation. Ordinarily, the principal use of the more volatile fuel is for starting the engine, or for running the same at very low speeds, as under average operating conditions the heavier fuel can be used more economically. It is advisable, however, after running on the heavier fuel, to reverse the positions of the valves 21 and 22 before stopping the engine, in order that the priming-cup 42 may be filled with the lighter fuel when the controller is moved to closed position. The coördinated action of the throttle, fuel-controller and deflecting-valve insures a uniform mixture at all times, the supply of fuel being automatically proportioned to the volume of air passing through the distributing and mixing chambers, while the deflecting-valve causes the charge to pass into the mixing-chamber with uniform velocity regardless of the extent of opening of the throttle. Thus, when the throttle is wide open the area of the passage around the deflecting-valve is greatest, and said area is reduced proportionally to the closure of the throttle, resulting in the rate of flow of the charge past the valve being equalized for all positions of the throttle. The air and fuel in passing through the tortuous passage around the deflecting-valve, through the deflecting-plate 51, and through the screens in the mixing-chamber, are thor-

oughly commingled and any liquid particles of the fuel are broken up or atomized so that vaporization thereof will occur prior to the admission of the charge to the engine. 5 The disintegration or atomizing of the fuel is also facilitated by the injection thereof through a plurality of separate openings, whereby the same is spread out or distributed throughout the in-rushing air-column, 10 as distinguished from the ordinary types of carbureters wherein the fuel is admitted through a single jet.

Now, having described our invention, what we claim and desire to secure by Letters Patent is:

1. In a carbureter, a vertically-disposed tubular distributer-body having a plurality of transverse passages extending radially through the sides thereof, means for supplying liquid fuel to said passages, a casing inclosing the distributer-body and adapted to direct an air-current through and around the distributer-body past both ends of the transverse passages, and a rotary controller adapted to serially close and open said ends of the passages.

2. In a carbureter, a casing inclosing a distributer-chamber and a mixing chamber in superposed relation and having a constricted neck-portion between said chambers, variable fuel-supplying means disposed in the distributer-chamber, stationary charge-communuting means disposed in the mixing-chamber, a movable deflector disposed in the constricted neck-portion and adapted to vary the sectional area of the passage through the same, a throttle controlling an outlet from the mixing-chamber, and means connecting the throttle, the movable deflector and the variable fuel-supplying means, whereby adjustments thereof are automatically coördinated.

3. In a carbureter, a casing having therein an air chamber, a distributer-chamber and a mixing-chamber in successively superposed relation, means for supplying pre-heated air to the air-chamber so that the same may be drawn therefrom through the distributer-chamber and mixing-chamber, means for supplying liquid fuel to a plurality of passages opening into the distributer-chamber, a controller movable to serially open and close the openings of the fuel-passages into the distributer-chamber, charge-communuting devices disposed in the mixing-chamber, a throttle controlling an outlet from the mixing-chamber, and connecting means for positively actuating the throttle and controller simultaneously so that the number of fuel-passages opened by the controller is proportional to the extent of opening of the throttle.

4. The combination in a carbureter, of a casing having two fuel-chambers therein, a

multiple-opening fuel-distributer, means for interchangeably connecting the fuel-chambers with said distributer, a movable controller for serially opening and closing the fuel-openings of the distributer, means for supplying preheated air and for directing the same past the distributer fuel-openings, means for pre-heating the fuel supply for one of the fuel-chambers, means for heating said fuel-chamber, and means for supplying water-vapor together with the pre-heated air.

5. In a carbureter, multiple-opening fuel-supplying means, a movable member for serially covering and uncovering the openings of said fuel-supplying means, a priming-cup, and means on the movable member for controlling a port connecting the fuel-supply with the priming-cup.

6. In a carbureter, a fuel-distributer comprising a vertical tubular member having a plurality of radial passages therein, means for supplying liquid fuel to said passages, a casing inclosing said distributer and arranged in spaced concentric relation thereto, the casing being adapted to direct air through and around the tubular member past both ends of the radial passages therein, means for controlling the flow of air through the casing, and means for serially covering the ends of the radial passages in the tubular member.

7. In a carbureter, a fuel-distributer comprising a tubular member having a plurality of radial ports therein, means for supplying liquid fuel to said ports, an annular priming-cup extending around the tubular member adjacent to some of said ports, there being a port for supplying fuel to the priming-cup, and a rotary member movable to control the openings of the ports, including the port for supplying the priming-cup.

8. In a carbureter, a casing having superposed chambers therein, fuel-distributing means disposed in the lower chamber, charge-mixing means disposed in the upper chamber, deflecting means forming a tortuous passage connecting said chambers, means controlling the deflecting means to vary the sectional area of the tortuous passage, and means for controlling the flow of air through the casing, said means connected with and movable coincidently with the means controlling the deflecting means.

9. In a carbureter, a casing, means connected therewith for supplying thereto pre-heated fuel and air together with water-vapor, means for distributing the fuel to bring the same in contact with the air passing through the casing, means controlling the flow of air through the casing, charge-communuting means through which the air and fuel are drawn from the distributing means, a stationary and a movable deflecting

device disposed between the distributing means and the charge-comminuting means, and means controlling the movable deflecting device to vary the sectional area of the opening past the same and thereby control the rate of flow of the charge in passing to the comminuting means.

In testimony whereof we have hereunto

subscribed our names in the presence of two witnesses.
